DESIGN FOR AN AUTOMOBILE BODY

John W. Sparkman, Birmingham, Ala.

Application September 21, 1935, Serial No. 58,638

Term of patent 14 years

To all whom it may concern:

Be it known that I, John W. Sparkman, a citizen of the United States, residing at Birmingham, in the county of Jefferson and State of Alabama, have invented a new, original, and ornamental Design for an Automobile Body, of which the following is a specification, reference being had to the accompanying drawing forming a part thereof.

In the drawing,

The single figure in the drawing shows a perspective view of the automobile body of my new design.

The dominant feature of my design resides in the door and its relation to the surrounding portions of the automobile body.

I claim:—

The ornamental design for an automobile body, substantially as shown and described.

JOHN W. SPARKMAN.
